UNITED STATES PATENT OFFICE.

TELEMACO FERELLA, OF MONESSEN, PENNSYLVANIA.

PROP OR STAND FOR BICYCLES.

1,163,592.

Specification of Letters Patent.

Patented Dec. 7, 1915.

Application filed March 8, 1915. Serial No. 12,991.

To all whom it may concern:

Be it known that I, TELEMACO FERELLA, a citizen of the United States, residing at Monessen, in the county of Westmoreland and State of Pennsylvania, have invented 5 certain new and useful Improvements in Props or Stands for Bicycles, of which the following is a specification, reference being had to the accompanying drawings.

10 This invention relates to certain improvements in props or stands for bicycles, preferably motor cycles; and an object of the invention is to provide a device of this general character having novel and improved means whereby the device is under control 15 of the seat of the cycle.

Furthermore, it is an object of my invention to provide a device of this general character including a novel and improved foot 20 which automatically assumes a position angular to the cycle proper when in operative position and which automatically assumes a position substantially parallel to the cycle when in inoperative adjustment.

25 It is also an object of my invention to provide a novel and improved prop or stand which is automatically operated to assume an operative position and which may be either manually or automatically adjusted 30 into an inoperative position.

The invention consists in the details of construction and in the combination and arrangement of the several parts of my improved prop or stand whereby certain important advantages are attained and the device is rendered simpler, less expensive and otherwise more convenient and advantageous for use, all as will be hereinafter more fully set forth.

40 The novel features of the invention will be carefully defined in the appended claims.

In order that my invention may be the better understood, I will now proceed to describe the same with reference to the accompanying drawings, wherein—

Figure 1 is a fragmentary elevational view of the rear structure of a conventional motor cycle having applied thereto a stand or prop constructed in accordance with an 50 embodiment of my invention; Fig. 2 is an enlarged fragmentary view, partly in elevation and partly in section, illustrating certain details of the operating means for my improved prop or stand as herein set forth; 55 Fig. 3 is a fragmentary view, partly in rear elevation and partly in section, illustrating

props or stands constructed in accordance with my invention in operative adjustment; Fig. 4 is a fragmentary view, partly in elevation and partly in section, illustrating one 60 of my improved props or stands adjusted in an inoperative position and illustrating in detail a portion of the operating means therefor and a locking means adapted to coact therewith; Fig. 5 is an enlarged detail 65 sectional view taken substantially on the line 5—5 of Fig. 2; Fig. 6 is an enlarged detail sectional view taken substantially on the line 6—6 of Fig. 1; and Fig. 7 is an enlarged 70 sectional view taken substantially on the line 7—7 of Fig. 2.

As disclosed in the accompanying drawings, F denotes the rear portion of a conventional frame for motor cycles having coacting therewith the seat structure S yieldably supported in a well known way, as indicated at 1 in Fig. 2, by the seat post 2 of the frame whereby said seat structure is capable of movement in substantially a vertical plane, the weight of the occupant of the 80 seat causing a substantially downward movement of the seat S, for a purpose which will hereinafter be more particularly referred to.

Depending from the rear extremity of the 85 frame F at opposite sides thereof is a tubular post 3 terminating a predetermined distance above the contacting portion of the tread of the rear wheel structure W. Mounted within the lower extremity of the 90 tubular member 3 and capable of reciprocatory movement therein is a shank 4 projecting beyond the lower end of the tubular member 3 and terminating in the angular foot 5. The shank 4 is provided with a 95 spiral slot 6 through which projects a pin 7 carried by the lower extremity of the tubular member 3 and it is to be observed that the slot 6 is disposed on such a pitch that when the shank 4 is moved upwardly within the tubular member 3, the foot 5 will be caused to assume a position substantially parallel to the frame F, and upon imparting downward movement to the shank 4 the foot 5 will assume a position at substantially 100 right angles to the frame, as is particularly illustrated in Fig. 3, said latter adjustment being the position the foot 5 assumes when it is adapted to engage the supporting surface, for a purpose which is believed to be 105 self-evident.

Downward movement to the shank 4, as

herein disclosed, is created under the influence of an expansible member 8, herein disclosed as a conventional coil spring, positioned within the tubular member 3 and interposed between the inner extremity of the shank 4 and the upper closed head 9 of said member 3, as is particularly shown in Fig. 4. The shank 4 at a point above the upper extremity of the slot 6 is provided with the recess or cavity 10 adapted to receive the forwardly projected lug 11 carried by the latch member 12 mounted for reciprocatory movement within the tubular bracing post 14 interposed between the lower extremity 15 of the tubular member 3 and an adjacent bar 15 of the frame F, said latch member being automatically moved toward the shank 4 under the influence of the expansible member 16 positioned within the tubular bracing post 14 and interposed between the inner or upper extremity of the latch member 12 and the septum 17 intersecting the bore of said bracing post 14, as is also particularly shown in Fig. 4.

25 The latch member 12 has secured thereto the elongated member 18 which is disposed within and longitudinally of the bracing post 14 and intersects the adjacent bar 15 of the frame and terminating thereabove, 30 said bar 15 being provided with suitable openings 19 for the passage of said member 18. The upper extremity of the elongated member 18 has secured thereto the flexible member 20 also secured to the forwardly 35 disposed angular extremity 21 of the lever 22 whereby it will be readily perceived that upon imparting the requisite movement to the lever 22, the latch member 12 will be disengaged from the shank 4. The flexible 40 member 20 has interposed therein a tensioning member 23, for a purpose which is believed to be self-evident.

Suitably secured to the inner or upper extremity of the shank 4 is an elongated member 24 projecting through and terminating above the upper extremity of the tubular member 3 and having secured to said upper or projected extremity a flexible member 25 disposed over the idler guide pulley 26 and 50 operatively engaged with a drum 27 suitably secured to the shaft 28 affixed to the upper bars 29 of the frame F and disposed transversely thereof.

As is particularly illustrated in Fig. 5, the 55 drum 27 is loosely mounted upon an extremity of the shaft 28 and is provided with a clutch face 30 adapted to coact with a clutch member 31 fixed to the shaft 28. The drum 27 is also capable of limited longitudinal movement upon the shaft 28 in order to permit disengagement thereof from the clutch member 31 so that the tension of the flexible member 25 may be regulated. The drum 27, or more particularly the clutch 65 face 30 thereof, is normally maintained in

operative engagement with the clutch member 31 under the influence of the expansible member 32, herein disclosed as a conventional coil spring, interposed between the drum 27 and an annular member 33 keyed 70 to the outer end of the adjacent extremity of the shaft 28. As herein disclosed, the outer face of the hub 34 of the drum 27 is recessed, as at 35, in order to permit the desired movement of the drum longitudinally 75 of the shaft 28. As herein disclosed, the shaft 28 is rotatably supported in the upstanding bearings 36 carried by the plate 37 overlying the bars 29 and through which is disposed the clamping member 38 also directed through the second plate 39 underlying the bars or tubes 29 and coacting with the clamping member 38 is a conventional nut or bur 40, whereby it will be perceived that an effective and convenient mounting is 85 afforded for the shaft 28.

Loosely engaged with the shaft 28 intermediate a bearing 36 and an adjacent clutch member 31 is a guide 41 substantially U-90 shape in cross section and in which is slidably positioned the rack member 42 in mesh with the pinion 43, herein disclosed as integrally produced with the shaft 28. As is believed to be self-evident, rearward movement of the rack member 42 will result in 95 such axial rotation of the shaft 28 as to cause an elevation of the shank 4. As herein embodied, the rear extremity of the rack member 42 has pivotally engaged therewith the rigid link 44 which is also pivotally engaged with the depending angular portion 45 of the lever 46 pivotally engaged with the forward upper bar or tube 47 of the frame F. Upon elevating the lever 46, as is shown particularly in Fig. 2, the shaft 100 28 will be rotated sufficiently to permit the foot 5 to operatively engage, in a manner hereinbefore set forth, the supporting surface, and upon adjustment of the lever 46 to overlie the bar 47, as is particularly 110 shown in Fig. 1, the shaft 28 will be sufficiently rotated to properly elevate the foot 5.

In order to maintain the lever 46 in its overlying adjustment relative to the bar 47, I provide the yoke member 48 straddling the bar 47 and pivotally engaged therewith, as at 49, see Fig. 7, and which is adapted to overlie the forward upstanding extremity 50 of the lever 46. The yoke 48, however, is normally maintained in an inoperative 120 position, see Fig. 2, under the influence of the spring 51, one extremity whereof being anchored to the bar or tube 47 while the opposite extremity thereof is in proper engagement with the yoke 48, the intermediate 125 portion of said spring being coiled, as at 52, about the pivot 49. A pivoted extremity of the yoke 48 is provided with the rearwardly disposed lug 53 with which the downwardly directed lug 54 carried by the forward ex- 130

tremity of the lever 46 is adapted to contact, whereby it will be perceived that the yoke 48 will be caused to operatively coact with the extremity 50 of the lever 46 and 5 maintain said lever in its overlying adjustment relative to the bar 47. Also pivotally engaged with the rear extremity of the rack member 42 is the rigid link 55, the upper extremity of said link being provided with 10 an elongated longitudinally disposed slot 56 through which is disposed a pin 57 projecting laterally from the bar 58 comprised in the seat structure S, the forward extremity of said bar 58 being also pivotally engaged with the bar 47 whereby it will be perceived that movement of the rack 42 under the influence of the weight of an occupant of the seat structure S will only occur when the lever 46 is in an elevated position. 15 With the lever 46 adjusted in overlying position relative to the bar 47, it will be observed that the elongated slot 56 will permit the requisite vertical vibratory action of the seat structure. 20

25 From the foregoing description, it is thought to be obvious that a prop or stand constructed in accordance with my invention is of an extremely simple and comparatively inexpensive nature and is particularly well adapted for use by reason of the convenience and facility with which it may be assembled, and it will also be obvious that 30 my invention is susceptible of some change and modification without material departure from the principles and spirit thereof and for this reason I do not wish to be understood as limiting myself to the precise arrangement and formation of the several parts herein shown in carrying out my invention in practice.

I claim:

1. In combination with a cycle frame and a seat structure supported by the frame and movable relative thereto, a vertically movable prop, and means operable upon depression of the seat for imparting upward movement to the prop in one direction. 45
2. In combination with a cycle frame and a seat structure supported by the frame and 50 movable relative thereto, a vertically movable prop, means operable upon depression of the seat for imparting upward movement to the prop, and mechanism for relieving

said means from action under the influence of the movement of the seat. 55

3. In combination with a frame, a prop operatively engaged therewith and mounted for reciprocating movement, a drum carried by the frame, a flexible connection between the drum and the prop, an endwise movable member operatively engaged with the drum, and a seat structure supported by the frame and movable relative thereto, an operative connection between the seat structure and the endwise movable member whereby said member is moved in one direction upon depression of the seat structure. 60 65

4. In combination with a frame, a prop operatively engaged therewith and mounted for reciprocating movement, a drum carried by the frame, a flexible connection between the drum and the prop, an endwise movable member operatively engaged with the drum, a seat structure supported by the frame and movable relative thereto, an operative connection between the seat structure and the endwise movable member whereby said member is moved in one direction upon depression of the seat structure, and manually operated means for holding said endwise movable member against movement in a direction opposite to the first named movement. 70 75

5. In combination with a frame, a prop operatively engaged therewith and mounted for reciprocating movement, a drum carried by the frame, a flexible connection between the drum and the prop, an endwise movable member operatively engaged with the drum, a seat structure supported by the frame and movable relative thereto, an operative connection between the seat structure and the endwise movable member whereby said member is moved in one direction upon depression of the seat structure, and manually operated means for holding said endwise movable member against movement in a direction opposite to the first named movement. 80 85 90

95 100
In testimony whereof I hereunto affix my signature in the presence of two witnesses.

TELEMACO FERELLA.
